UNITED STATES PATENT OFFICE.

PHILIP J. MITTEN, OF OAKWOOD VILLAGE, OHIO, ASSIGNOR TO THE RECORDING REGISTER AND FARE BOX COMPANY, OF NEW HAVEN, CONNECTICUT, A CORPORATION OF CONNECTICUT.

FARE-BOX.

1,110,268.

Specification of Letters Patent. Patented Sept. 8, 1914.

Application filed February 28, 1914. Serial No. 821,650.

To all whom it may concern:

Be it known that I, PHILIP J. MITTEN, a citizen of the United States, residing at Oakwood Village, in the county of Montgomery and State of Ohio, have invented certain new and useful Improvements in Fare-Boxes, of which the following is a specification, reference being had therein to the accompanying drawing.

This invention relates to fare boxes and more particularly to the hopper or upper portion of the fare box which first receives the coins and which constitutes an inspection box where the coins are held temporarily for inspection by the conductor, or other collector, and the passenger. Fare boxes are usually removably mounted upon their supports and are sometimes portable. In either case it has been found necessary to provide means to prevent the coins being removed from the hopper without being deposited into the till or registering mechanism, as the case may be, upon which the hopper is mounted and with which it communicates. Many devices have been provided to prevent the illicit removal of coins from the fare box but in most instances it is possible to defeat the purpose of these devices and to remove the coins. Where means are provided to prevent the coins being poured out of the box when it is inverted the box may be manipulated in such a manner as to toss the coin through the inlet opening and then quickly tilt the box to prevent the coin gravitating back through the inlet opening. It is then a comparatively simple matter to remove it from the slot or coin opening in the top of the hopper.

The present invention is in the nature of an improvement on the fare box shown and described in the application filed by Ohmer and Kist October 2nd, 1913, Ser. No. 792,934, and the object of the invention is to provide means which will not only prevent the coin being removed by the inversion of the box but will prevent the coin being tossed back through the inlet opening or in any way carried back through that opening.

A further object of the invention is to

provide such a device which will effectually close the inlet opening against the outward movement of a coin when the fare box is tilted from its upright position, in any direction; and further, to provide a very simple method of mounting the guards which will hold the guards firmly in position but will allow them to have free swinging movement; and which can be very quickly placed in position, thus facilitating the assembling of the device.

In the accompanying drawings, Figure 1 is a side elevation of the upper portion of a fare box showing my invention applied thereto; Fig. 2 is a sectional view taken on the line *x-x* of Fig. 1 and looking in the direction of the arrows; Fig. 3 is a vertical sectional view taken centrally through the hopper or upper portion of the fare box; Fig. 4 is a sectional detail view of the guard fingers; Fig. 5 is a detail view, partly in section, of the support for the guard fingers; Fig. 6 is a plan view of the same; Fig. 7 is a detail view of one of the guards; and Fig. 8 is a detail view of the clamping ring for securing the guards in position.

In these drawings a single embodiment of the invention is illustrated and the invention is shown as applied to a fare box of the type shown and described in the above mentioned application, but it will be understood that this particular form of fare box is chosen for the purpose of illustration only and that the invention is applicable to fare boxes or receiving hoppers of different kinds. In these drawings I have shown only the upper portion of the fare box proper, which is indicated at 1 and is preferably in the nature of a recording fare box which makes and preserves a record of the coins which pass through the same. Mounted upon the body portion 1 of the fare box is an inspection box or hopper 2 which is preferably rectangular in cross section and formed of glass walls. The hopper is provided at its top with a closure 3 having an annular series of openings 4, each opening being of a size sufficient to receive the largest coin that the box is designed to handle. The hopper communicates at its lower end

with the fare box proper and this communication is controlled by a spring-actuated door 5 mounted on a shaft 6 and held normally in its closed position by a spring 7. 5 Depending from the closure 3 and secured thereto centrally of the annular series of openings 4 is a deflector 8 having downwardly diverging walls which project laterally a distance sufficient to bring them into 10 the paths of coins entering the hopper through the openings 4 in the closure. In the present instance the deflector is in the shape of a truncated cone having its small end secured to the closure 3. A second deflector 15 9 is supported within the hopper some distance below the deflector 8 and has its walls converging downwardly and provided with a central opening 10 arranged directly beneath the upper deflector 8, this opening being of a size to permit the passage of any 20 coin which can pass through the openings 4 of the closure. In this instance also the deflector is in the form of a truncated cone which, as here shown, is inverted and is provided with substantially parallel side portions 25 extending upward and secured to the hopper near the top thereof. It will be understood that the manner of mounting this second deflector is optional and does not 30 form a part of the invention.

In order to prevent coins being caused to pass back through the opening 10 in the lower deflector 9 we have provided this opening with a series of movable guard 35 members so arranged about the same that when the hopper is tilted in any direction one or more of these fingers will move by gravity across the opening 10 and thus close the opening against the passage of a coin from the lower side thereof. In the present 40 instance, inasmuch as the opening is a round one and forms the small end of a truncated cone the guards are arranged in annular series about the same. As here shown each 45 guard comprises a finger 11 provided at its upper end with an eye 12 by means of which it is pivotally mounted on a ring 13 suitably secured to the deflector. In the form of the device here shown an annular supporting 50 frame 14 is rigidly secured to the lower portion of the deflector, about the opening 10, and has an annular groove 15 extending about the inner face thereof, which groove is intersected at intervals by vertical slots 16 55 adapted to receive the eyes 12 of the guard fingers, while the annular groove 15 is of a size and shape to receive the ring 13. The ring 13 is an open ring of resilient material and is adapted to have the guard fingers 60 strung thereon and then to be sprung into position in the groove 15 with the eye of each guard finger in its slot 16. The depth of the groove 15 is such as to prevent the ring from exerting any material pressure on 65 the eyes of the rings and thus causing a fric-

tion which would interfere with its free swinging movement. On the contrary, the fingers are so mounted that they move with the utmost ease and will promptly follow any tilting of the hopper. The fingers are held in their normal positions and limited in their outward movement by means of an apron or depending flange 17 carried by the annular supporting frame 14 and terminating a short distance above the lower ends of the guard fingers. The shape of this apron is preferably such as to cause the fingers to converge slightly toward the axis of the inlet opening 10. In order that a coin may not be accurately positioned on the spring-actuated trap door 5 and then flipped through the opening 10 by opening this door carefully and allowing it to move quickly to its closed position, a projection, such as a cone 18, is mounted on the door in direct line with the opening 10. The coin can only be thrown through the opening in this manner by being accurately positioned on the door and this cone prevents the coin being so positioned and, consequently, prevents it being thrown through the opening in this manner.

It will be apparent that after the coin has been deposited in the hopper and has passed the defectors it will be exceedingly difficult, if not impossible, to remove it. The mere inversion of the hopper will only cause the coins to roll into the space between the converging walls of the deflector 9 and the walls of the hopper. If an attempt is made to so manipulate the hopper as to cause the coins to be tossed through the opening in the deflector the guard fingers will almost certainly be moved across the opening, as it is practically impossible to so manipulate the hopper without tilting the same and any movement of the hopper from the upright position causes one or more of the guard fingers to extend across the opening. Further, the cone or projection 18 prevents a coin from being positioned directly beneath the opening and thus thrown straight up through the opening, either by manipulating the door or by manipulating the fare box in a straight vertical line, if this is possible. In order that any attempt to manipulate the hopper in such a manner as to illicitly remove the coins may be detected a tell-tale is provided in the form of a weighted pin 19 which is loosely mounted in an apertured bracket 20 and so arranged that it will remain normally in the socket but will be displaced by the manipulation of the hopper, as above described.

I am aware that pivoted guard fingers have been employed in hoppers for fare boxes, as illustrated in the patent to Yeo and Bohl, No. 1,063,758, of June 3rd, 1913, but the arrangement there shown is not such as to accomplish the results of the present

invention which contemplates a single opening with a single series of guard fingers arranged to close that opening when the hopper is tilted in any direction.

5 While I have shown and described one embodiment of my invention it will be understood that this has been chosen for the purposes of illustration only and that I do not desire to be limited to the details of 10 construction shown and described, for obvious modifications will occur to a person skilled in the art.

Having thus fully described my invention, what I claim as new and desire to secure by 15 Letters Patent, is:—

1. In a device of the character described, a receptacle to receive coins, a deflector mounted in said receptacle and having a single opening to permit the passage of 20 coins therethrough, and guards mounted adjacent to said opening and so supported and arranged that the tilting of said receptacle in any direction will cause one or more of said guards to extend across said opening.

25 2. In a device of the character described, a receptacle to receive coins, a deflector mounted in said receptacle and having an opening to permit the passage of coins therethrough, and guard fingers loosely supported on four sides of said opening, whereby 30 the tilting of said receptacle in any direction will cause one or more of said guards to extend across said opening.

3. In a device of the character described, 35 a receptacle to receive coins, a deflector having downwardly converging walls terminating in an opening, guard fingers pivotally mounted on said deflector and projecting beneath said opening, said guard fingers being so mounted and arranged that when 40 said receptacle is tilted in any direction one or more of said fingers will move by gravity across said opening.

4. In a device of the character described, 45 a receptacle to receive coins, a deflector mounted in said receptacle and comprising an inverted truncated cone having its smaller end open, an annular series of guard fingers loosely mounted about said opening and depending beneath the same, whereby the tilting 50 of said receptacle will cause one or more of said fingers to extend across said opening.

5. In a device of the character described, 55 a receptacle to receive coins, a deflector mounted in said receptacle and having downwardly flared walls, a second deflector mounted in said receptacle and having downwardly converging walls, said second deflector being arranged beneath the first- 60 mentioned deflector and having a discharge opening arranged centrally of the first-mentioned deflector and of a diameter less than the diameter of the lower portion of said first-mentioned deflector, and guard fingers so mounted and arranged adjacent to said

opening that the movement of said receptacle in any direction from an upright position will cause one or more of said fingers to extend across said opening.

6. In a device of the character described, 70 a receptacle to receive coins, a deflector mounted in said receptacle and having downwardly converging walls terminating in an opening, an annular supporting frame mounted on the lower portion of said deflector, and a plurality of guard fingers pivotally mounted at their upper ends on said annular frame and projecting beneath said opening.

7. In a device of the character described, 80 a receptacle to receive coins, a deflector mounted in said receptacle and having downwardly converging walls terminating in an opening, an annular supporting frame mounted on the lower portion of said deflector, and a plurality of guard fingers pivotally mounted at their upper ends on said annular frame and projecting beneath said opening, said guard frame having a depending portion arranged to engage said fingers 90 near their lower ends and limit the outward movement thereof.

8. In a device of the character described, 95 a receptacle to receive coins, a deflector mounted in said receptacle and having downwardly converging walls terminating in an opening, an annular supporting frame mounted on the lower portion of said deflector, and a plurality of guard fingers pivotally mounted at their upper ends on 100 said annular frame and projecting beneath said opening, said guard frame having a depending portion arranged to engage said fingers near their lower ends, that part of said depending portion which engages said 105 fingers being of less diameter than said annular frame, whereby said fingers are caused to converge downwardly.

9. In a device of the character described, 110 a receptacle to receive coins, a deflector mounted therein and having downwardly converging walls terminating in an opening, an annular frame mounted on said deflector and extending about said opening, said frame having an inner annular groove and 115 vertical slots intersecting said groove, a plurality of guard fingers having eyes at their upper ends, and a resilient ring adapted to enter the eyes of said fingers and to be sprung into said groove to retain said 120 fingers in said vertical slots.

10. In a device of the character described, 125 a receptacle to receive coins, a deflector having an opening therein, a spring actuated door to close the bottom of said receptacle, and a projection secured to said door in alinement with the opening in said deflector.

11. In a device of the character described, 130 the combination, with a receptacle to receive coins, a deflector mounted therein and hav-

ing an opening, guard fingers arranged about said opening to be moved across the same when said receptacle is tilted, a bracket having a socket, and a weighted pin mounted in said socket and adapted to be displaced by the tilting of said receptacle.

In testimony whereof, I affix my signature in presence of two witnesses.

PHILIP J. MITTEN.
